CHESTER C. HOWE, OF NEW KENSINGTON, PENNSYLVANIA, ASSIGNOR, BY MESNE ASSIGNMENTS, TO FRANK R. ALTER, OF PARNASSUS, PENNSYLVANIA.

WASHING MACHINE.

Application filed March 7, 1923. Serial No. 623,378.

This invention is for an improvement in washing machines, and relates particularly to a brush washing machine structure for use in combination with a power driven 5 agitating washer having a wringer operated from the same source of power as the agitating washer.

Most washing machines built for domestic use at the present time have the reversible 10 power driven wringer arranged to swing in a horizontal plane to a plurality of different operating positions. This enables the wringer to wring clothes from the machine into a tub, or from one tub into another tub, 15 or from a tub into a basket, the wringing operations being made, when desired, in all cases except the first, with the agitating washer in operation.

The present invention proposes as its principal object to combine with the wringer thus mounted and driven, a brush washer, the combination being effected in such manner as to provide a compact structure with the wringer arranged above the revolving 25 brush and so disposed that water therefrom will not fall onto the brush, and yet be so mounted as not to obstruct the operator's view of the brush, or be so high above the brush as to present an unwieldy appearance. 30 The brush and wringer are both geared to a vertical drive shaft in such manner that they may be swung in a horizontal arc thereabout, while maintaining driving relation therewith.

The invention may be understood by referring to the accompanying drawing, in which:

Fig. 1 is a side elevation of a washing machine embodying my invention;

Fig. 2 is a side view of the gearing and housing therefor for driving the brush and the wringer, the cover plate for the housing being removed;

Fig. 3 is a section in the plane of line 45 III—III of Fig. 2;

Fig. 4 represents an end view of the brush housing.

In the drawing, 5 designates a supporting frame on which is carried a tub 6. Below 50 the tub, on the frame, is a motor 7 which drives a vertical shaft 8 contained in a tubular housing 9 extending up one side of the frame. At 10 is the gear housing which

incloses the mechanism for reversibly rotating the tub, such gearing forming no part 55 of the present invention and not, therefore, being illustrated.

At the top of the housing is a projecting part 11 having machined bearing surfaces at 12, which provide bearings for the sleeve 13 60 on the wringer and brush support 14.

The wringer and brush support is preferably an integral cast structure having a chamber 15 therein. The upper part of the chamber is offset, as indicated at 16. This 65 chamber is preferably substantially square in horizontal cross section, having two sides 17 and 18, and two faces 19 and 20. Side 18 is preferably removable, to give access to the interior of the chamber. The side 17, instead of being flat across its width, has an integral offset portion or face 17^a.

Secured to the side 17 of the housing is the end plate 21 of the brush washer and wringer frame, the upper part of the wringer 75 frame being further secured to the support by screw 22 passing through integral lugs on the support and frame, respectively. The brush washer and wringer frame includes a horizontal beam 24, and 25 (see 80 Fig. 4) is the end plate which is secured to the end of the beam by bolts which pass through holes 26 therein. A brush carrying shaft 27 is journalled in plate 25 and passes through the end plate 21 and has a bearing 21^a in the support 14. The inner end of this shaft terminates in chamber 15. On the shaft 27 is a brush 28. 29 is a scrubbing roll which holds the clothes 85 against the brush, the structure of the brush washer being shown in my copending application filed September 23, 1922, Serial No. 590,005.

The wringer has upper and lower rolls, 30 and 31 respectively, and the two rolls are 90 preferably geared together in the usual manner, the gearing not being shown but being retained. The shaft of the lower roll 31 is connected at coupling 32 with a stub shaft 33 journaled in the support 14, in the offset 95 part thereof.

The wringer has oppositely sloping drain boards 34 and 35. These drain boards must have sufficient slope to return the water to the tubs from which the clothes being wrung are 100 taken. They must be long enough so that the 105

water will not fall on the brush washer and splash around. By providing the offset portion 16 in housing 14, the shaft for driving the wringer is in proper vertical alinement 5 for driving the wringer, but the wringer can be set forward over the front of the brush. Drain board 34 may then have the proper degree of slope to drain the water from the wringer, and may be short enough that it will 10 not extend down so far that the view of the operator of average height would be obstructed, and yet will be of sufficient length that the water will not fall on the brush washer. If the offset in the support 14 were 15 not provided, the drain board 34 would have to be so long that the operator's view of the brush would be cut off. Drain board 35 may be of any desired length, as the brush is not operated from that side of the machine. 20 The shaft 8 projects up into the chamber 15. At 40 is a bevel gear wheel loose on the shaft 8. This wheel meshes with a similar, but smaller, gear on the brush shaft 27. Splined on the vertical shaft 8 is a clutch 41 having pins 42 for engagement with recesses in the face of gear wheel 40. This clutch is operated through feather 43 and rock shaft 44 from a crank or lever 45 on the outside of the casing 14. By operation of the clutch, 25 the brush may be driven from shaft 8 at a much higher speed than that at which shaft 8 revolves.

On the end of shaft 8 is a bevel gear 46 which meshes with two oppositely disposed gear wheels 47 and 48 loose on a stub shaft 49, whereby the wheels 47 and 48 are driven in opposite directions. Splined on the shaft 49 between the two wheels 47 and 48, is a clutch member 50 which may be shifted into 30 engagement with one or the other of said wheels, to impart rotation to the shaft.

The clutch member 50 is shifted by means of yoke 51 on a transverse shaft 52 whose ends project beyond the casing and are provided with cranks 53 and 54. Crank 53 extends in a direction diametrically opposite to crank 54. The advantage of this is that, 35 no matter which side of the wringer the operator is on, she may move one of the cranks always, we may assume, to the left to make the rolls turn away from her and to the right to make them turn toward her. This is a great convenience as, on most machines, the clutch lever must be operated in opposite directions, or relatively opposite directions when the operator changes from one side of the wringer to the other.

On the shaft 49 is a small gear wheel 55 which is fixed on the shaft. This gear wheel meshes with a larger gear wheel 56 on the shaft 33 in the offset part of the housing. This gearing not only allows the wringer to be offset out of lateral alinement with the plane in which the shaft 8 is located, as hereinbefore described, but provides a speed re-

duction for the wringer rolls, a feature which is desirable because of the relatively high speed at which the shaft 8 is operated to rotate the brush rapidly.

It will be seen from the arrangement described, the brush and wringer may be swung in a horizontal plane in a circle, with the axis of shaft 8 as its center. At 60 is a clamping bolt by means of which the wringer and brush support may be clamped 75 to hold it frictionally against rotation.

The two end members of the brush frame are connected by a lower rod 61. At 62 is a guard which extends around the rear of the brush to catch water and dirt thrown off by the brush and return it to the receptacle over which the brush is operating. This guard has a part 63 extending around the rod 61 so that the guard hinges thereon. The guard is held in place by screws 64 having winged heads to facilitate their removal, these screws passing through the guard and threading into the end frame member. Upon removal of the screws, the guard may be swung down and access had to the 85 interior thereof, whereby it may be cleaned.

Within the chamber 15 is a horizontal partition 65 which serves to divide the chamber into upper and lower compartments. This enables the gearing for the wringer to be run in grease and the gearing for the brush to run in grease, without necessitating that the entire chamber be filled. If the entire chamber were filled, it would be necessary to provide packing 95 around the brush clutch operating shaft.

Various changes and modifications may be made in the invention within the scope of the appended claims.

The brush washer and wringer frame with the brush and wringer rolls carried thereby constitute a laundry unit, and, as above described, this unit is rotatably mounted so that it may be swung in a horizontal plane and at the same time maintained in driving relation with a drive shaft. 105

What I claim is:

1. A supporting and operating device for laundry units, comprising a support, a rotatable casing carried thereon, a horizontal arm carried by the casing, gearing inside the casing, a horizontal shaft operated through the gearing below the arm, a second horizontal shaft above the arm and laterally off-set with respect to the first shaft 110 but parallel thereto.

2. Driving and supporting mechanism for wringers comprising a vertical shaft, a casing rotatable about the upper end of the shaft, an offset chamber in the top of the casing, a wringer operating shaft projecting from the offset portion of the casing, a reducing gear associated with the wringer shaft and received in the offset portion of the casing, a reversing gear driven from the 125

vertical shaft and operatively associated with the reducing gear, and a wringer supporting arm on the casing.

3. A supporting and operating means for laundry units including a supporting frame, a vertical drive shaft carried thereby, a casing rotatable about the drive shaft as a center, said drive shaft extending upwardly into the casing, a pair of bevel gears on the drive shaft one above the other, a laundry unit operating shaft driven by the lowermost bevel gear, a reversing gear operatively associated with the upper bevel gear, a reducing gear cooperating with the reversing gear, and a second operating shaft above the first shaft driven through the reducing gear.

4. A supporting and operating means for laundry units including a supporting frame, a vertical drive shaft carried thereby, a casing rotatable about the drive shaft as a center, said drive shaft extending upwardly into the casing, a pair of bevel gears on the drive shaft one above the other, a laundry unit operating shaft driven by the lowermost bevel gear, a reversing gear operatively associated with the upper bevel gear, a re-

ducing gear cooperating with the reversing gear, and a second operating shaft above the first shaft driven through the reducing gear, said lower gear having a larger diameter than the upper gear by means of which the lower shaft may be operated relatively faster than the upper shaft.

5. A supporting and operating means for laundry units including a supporting frame, a vertical drive shaft carried thereby, a casing rotatable about the drive shaft as a center, said drive shaft extending upwardly into the casing, a pair of bevel gears on the drive shaft one above the other, a laundry unit operating shaft in the lower part of the casing radially disposed with respect to the vertical shaft and having a gear meshing with the lowermost bevel gear, a reversing gear associated with the upper bevel gear, a reducing gear driven by the reversing gear and located above and to one side thereof, and a second shaft in the housing driven through the reducing gear, said shaft being above and to one side of the radially disposed shaft.

In testimony whereof I affix my signature.
CHESTER C. HOWE.
